GATE VALVE

William E. Lowrey and Clifford E. Anderson, Houston, Tex., assignors to ACF Industries, Incorporated, New York, N.Y., a corporation of New Jersey

Filed Apr. 26, 1965, Ser. No. 85,150

Term of patent 14 years

(Cl. D91—3)

FIG. 1.

FIG. 2.

FIGURE 1 is a perspective view of a gate valve, showing our new design.

FIGURE 2 is a plan view of the gate valve of FIGURE 1.

The opposite side and end views of the gate valve are substantial duplicates of the side and end views shown in FIGURE 1 with the exception of the substantially horizontal projection at the lower left corner of the valve and the substantially vertical and horizontal projections which are located at the upper portion of the valve.

This is a continuation-in-part of our co-pending design application, Serial Number 78,189, filed January 14, 1964, and now abandoned.

We claim:

The ornamental design for a gate valve, as shown and described.
